UNITED STATES PATENT OFFICE.

STEPHEN A. AKINS, OF KANSAS CITY, MISSOURI.

GAME.

1,171,916.

Specification of Letters Patent. Patented Feb. 15, 1916.

Application filed March 25, 1915. Serial No. 16,892.

To all whom it may concern:

Be it known that I, STEPHEN A. AKINS, a citizen of the United States, residing at Kansas City, in the county of Jackson and 5 State of Missouri, have invented certain new and useful Improvements in Games, of which the following is a specification.

My invention relates to a base ball game apparatus, and my object is to provide a 10 simple apparatus of this character which will accurately display, substantially, all plays that arise in a regular game of major league base ball.

The apparatus may be made in small sizes 15 for convenient use on small tables in the home, or it can be made in large sizes adapted to be suspended from the walls of public halls where the progress of games can be watched by many persons.

20 A game can be played on the apparatus by one or more persons without changing said apparatus in any particular.

In order that the invention may be fully understood, reference will now be made to 25 the accompanying drawings, in which:

Figure 1 is a plan view of the game. Fig. 2 is a longitudinal section on line II—II of Fig. 1. Fig. 3 is a broken longitudinal section of the game, with some of the parts 30 removed. Fig. 4 is a broken horizontal section on line IV—IV of Fig. 1. Fig. 5 is a longitudinal section on line V—V of Fig. 1. Fig. 6 is a detail of an annulus employed in carrying out the invention. Fig. 7 is an 35 enlarged section on line VII—VII of Fig. 1. Fig. 8 is one of a plurality of disks employed to display men on bases.

In carrying out the invention, I employ 40 a suitable case 1, in which the mechanism employed in playing the game is inclosed. The face-plate 1^a of said case 1 has a diamond 2 printed or otherwise produced thereon. Said diamond represents the usual base lines 3, the home-plate designated Home, 45 and the first, second, and third bases, designated 1—B, 2—B, and 3—B, respectively. Foul lines 2^a extend from the first and third bases to right and left fields, respectively. Openings C, 1—Bm, 2—Bm, and 3—Bm, are 50 formed in the face-plate 1^a adjacent the home-plate and the first, second, and third bases, respectively, for the display of the catcher, first baseman, second baseman, and third baseman of the out team. An opening S—S is formed in the face-plate 1^a,

between the second and third bases, to display the shortstops of the opposing teams in order, and an opening P is formed in the face-plate 1^a adjacent the center of the diamond 2 to display the opposing pitchers in 60 their regular turn. An opening Ump is provided in the face-plate 1^a, in the rear of the catcher's opening C, to display an umpire, and an opening B is formed adjacent the home-plate to display the different batters in their time at bat. The face-plate 1^a, also has openings arranged in proper relation to the openings above-referred to and designated R—F, C—F, and L—F, for the 65 display of the right, center, and left fielders, respectively.

The runners, or men on bases, are carried on disks 4, 5 and 6, arranged adjacent to the openings 1—B, 2—B, and 3—B, respectively. Each disk carries two different colored figures 7 and 8 to represent runners of the two opposing teams, distinguished from each other in the present instance by the titles Reds and Blues. For convenience in turning the disks to display red or blue 80 runners, each disk is mounted upon a knob 9, journaled in the face-plate 1^a. By thus independently mounting the disks 4, 5 and 6, all of the bases may be either shown clear or occupied with runners, or any one or 85 two bases may be shown occupied, as required during the progress of the game. The "red" and "blue" pitchers are carried on a disk 10 arranged beneath the opening P and mounted upon a knob 11, journaled 90 in the face-plate 1^a. The catchers, basemen, short-stops and outfielders of the two opposing teams are carried upon an annulus 12, the "reds" being designated R and 95 the "blues" B. The two umpires designated U, are also carried upon the annulus 12, which is rotatably mounted and surrounds 100 the disks 4, 5, 6 and 10.

The annulus 12 is rotated through the intermediacy of a knob 13 extending through 100 a segmental slot 14 in the face-plate 1^a, and said annulus is guided in its movements by its knob 13 and a plurality of pins 15 secured to the face-plate 1^a and extending through segmental slots 16 in the annulus. The annulus 12 has an inwardly-extending 105 tongue 17 to bring the "batters" of the opposing teams in proper relation to the batter's opening B. During the progress of a game the annulus 12 is shifted only at the 110

termination of each half inning to bring the opposing teams upon the field in their regular order.

18 designates an endless apron for displaying strikes, balls, fouls, fly-outs, bunts, single, double, and triple base hits, home-runs, and other plays occurring in the progress of a professional base ball game. Said endless apron 18 runs around rollers 19 and 20 journaled in the case 1 near the ends thereof.

The various plays carried upon the apron 18 and a number of which are indicated on Fig. 3, are arranged in column form and 15 for convenience are separated by horizontal and vertical lines 21 and 22, respectively. Said columns are arranged beneath display openings in the face-plate 1^a. Said display openings are normally closed by shutters 20 designating Bases clear, Men on 1 and 2 bases, Man on 1st base, Men on 1 and 3 bases, Man on 2nd base, Men on 2 and 3 bases, Man on 3rd base, and Bases full. By arranging the plays upon the apron 18 with proper 25 regard to said openings, impossible plays cannot occur, but on the contrary only such plays will be recorded in the progress of the game as actually occur in a professional game. The apron 18 is prevented from sagging away from the openings below the shutters by a sustaining plate 18^a, extending transversely across the interior of the case 1.

In order to prevent the apron 18 from slipping upon the rollers 19 and 20, I provide the ends of the roller 19 with sprocket-teeth 23, which successively pass through corresponding perforations 24 adjacent the margins of the apron. In the present instance the roller 19 is so proportioned that 35 each quarter revolution thereof advances the apron one step, or the distance between two horizontal lines 21, to successively bring the plays in coincidence with the openings under the shutters, and in order that it may be readily determined when said roller 19 has been turned one quarter of a revolution, I provide it with a four-toothed ratchet-wheel 25, coacting with a pawl 26 held in engagement therewith by a spring 27. The 40 pawl 26 not only prevents backward rotation of the ratchet-wheel 25, but the clicking sound which it produces when dropping from one tooth to another notifies the operator when the roller 19 has turned one-fourth of a revolution. For convenience in rotating the roller 19, the ends of its shaft are provided with hand-wheels 19^a.

The shutters designated "Bases clear," etc., normally close their respective openings, so that the party rotating the roller 19 cannot see any of the plays recorded on the apron 18, until he uncovers the proper opening, and consequently cannot knowingly stop said rotation to display points of highest value for the benefit of his team. Hence

the opposing parties playing the game will have an equal chance of winning the same. The shutters are mounted in slideways 28, secured to the underside of the face-plate 1^a, and each shutter has a stem 29 extending through the adjacent end of the case 1 and provided with a handle 30. The shutters are automatically closed and normally held in closed position by coil springs 31, embracing the stems 29 and interposed between the adjacent end of the case 1 and shoulders 32 on said stems 29.

33 designates score recording disks mounted upon knobs 33^a, journaled in the upper corners of the case 1. Each scoring disk 80 bears an annular row of numerals from 0 up to any number desired, which are displayed as required through openings 34 in the face-plate 1^a. The words "Reds score" are placed adjacent one opening 34 and the 85 words "Blues score" adjacent the other opening, so that the score of each team can be correctly kept.

The number of innings, outs, balls, and strikes are recorded by disks 35, 36, 37, and 38, respectively, arranged at convenient points within the case 1 and mounted upon knobs 39 whereby they may be readily rotated. The disk 35 has an annular row of numerals from 1 to 9 or more, which are displayed successively through an opening 40 in the face-plate 1^a, at the termination of each inning. The disk 36 bears numerals 1 to 3, inclusive, which are successively displayed through an opening 41 in the 100 face-plate 1^a, as each member of a team is put out. The disk 37 bears numerals 1 to 4, inclusive, adapted to be successively displayed through an opening 42 in the face-plate 1^a, to register the number of "balls" 105 called on each batter. Disk 38 has numerals 1 to 3, inclusive, to be successively displayed through an opening 43 in the face-plate 1^a, to register the "strikes" called on each batter.

Assuming that the game is to be played by two parties one of whom represents the "reds" and the other the "blues," the one entitled to the field is first determined by tossing a coin or any other suitable means. All of the disks are then rotated to show clear at their respective openings. If the "blues" are to bat first, the annulus 12 is rotated to display the "reds" at the in and out field positions. The party representing the "blues" then proceeds to rotate the hand-wheels 19^a as many revolutions as he desires, after which he opens the shutter designated "Bases clear." This exposes the play on the apron, which may be assumed as a "single." The disk 4 is then rotated to expose a "blue" runner at the first base opening. The first party then again rotates the hand-wheels 19^a as many revolutions as desired, after which he opens the slide des-

gnated "Man on 1st base" to find a play which may properly occur with the "blue" runner on first base. Assuming that the play disclosed by the apron shows a "double," the disk 4 is turned to clear and the disks 5 and 6 are turned to show "blue" runners at the second and third base openings. The first party then again rotates the hand-wheels 19^a as many revolutions as desired and opens the shutter designated "Men on 2 and 3 bases" to find a play which may properly occur with runners on the second and third bases. Assuming that the play exposed on the apron reads "Ball" and "Out trying to steal home," the disk 6 is rotated to show third base clear and the disk 36 is rotated until numeral 1 appears at the opening 41 to indicate one out. The disk 37 is also rotated to display its numeral 1. The first party then again rotates the hand-wheels 19^a as far as desired and opens the slide designated "Man on second base" to expose a play which may properly occur with the runner on said base. Assuming that the open shutter discloses the word "Ball" on the apron, the disk 37 is rotated until the numeral 2 appears at the opening 42. The first party then again rotates the hand-wheels 19^a and again opens the slide designated "Man on second base." Assuming that the word "Strike" appears on the apron at the opening, the disk 38 is rotated until the numeral 1 thereon appears at the opening 43. The first party then again rotates the hand-wheels 19^a and opens the slide indicating "Man on second base." Should the word "Double" be disclosed at the opening the disks 37 and 38 are rotated to clear position and the disk 33 is rotated to disclose score 1 for the "blues." The first party then again rotates the hand-wheels 19^a and opens the slide indicating "Man on second base" and if the opening discloses the words "2 outs" the disk 36 is turned to disclose the numeral 3 thereon. As the foregoing terminates the first half of the first inning the disks 5 and 36 are rotated to clear position and the annulus 12 is rotated to remove the "blue" players from the in and out field positions, and shift the "red" players to said positions. The second party then takes his position at the hand-wheels 19^a and proceeds in the same manner as the first party until three outs are registered. The disk 35 is then rotated to disclose the numeral 1 thereon to indicate that one full inning has been played. Thus the game proceeds, each party taking his turn at the hand-wheels 19^a until a full game of nine innings is played. Should the score result in a tie at the end of the ninth inning, extra innings may be played until one team attains a greater score than its opponent and thus wins the game.

65 While I have shown the preferred con-

struction, combination, and arrangement of parts, I reserve the right to make such changes as properly fall within the spirit and scope of the claims.

Having thus described my invention, what I claim and desire to secure by Letters Patent, is:

1. In an apparatus of the character described, a plate having certain openings through which different plays may be disclosed and other openings through which players of two opposing teams may be displayed in order in their respective in and out field positions, means beneath the last mentioned openings to display the players of the opposing teams as required, means beneath the first mentioned openings to indicate different plays that arise during the progress of the game, and shutters to normally close said first-mentioned openings.

2. In an apparatus of the character described, a plate having a representation of a base ball field thereon and openings through which players of two opposing teams may be displayed in order in their respective in and out field positions, means beneath said openings to display the players of the opposing teams as required, means beneath other openings in the plate to indicate different plays during the progress of a game, shutters to close the last-mentioned openings, slideways in which said shutters operate, means for opening said shutters, and means for closing said shutters.

3. In an apparatus of the character described, a plate having openings through which players of two opposing teams may be displayed in order in their respective in and out field positions, means beneath said openings to display the players of the opposing teams as required, an endless apron containing various plays, which arise during the progress of the game, means for shifting said apron, and means beneath other openings in the plate for uncovering the underlying plays.

4. In an apparatus of the character described, a plate having openings through which players of two opposing teams may be displayed in order in their respective in and out field positions, means beneath said openings to display the players of the opposing teams as required, an apron containing different plays arranged in columns, means for shifting said apron, and means beneath other openings in the plate for uncovering the underlying plays.

5. In an apparatus of the character described, a plate having openings through which players of two opposing teams may be displayed in order in their respective in and out field positions, means beneath said openings to display the players of the opposing teams as required, an endless apron containing various plays which arise during the

progress of a game, rollers over which said apron travels, means for rotating one of said rollers to shift the apron, and means beneath other openings in the plate for un- 5 covering the underlying plays.

6. In an apparatus of the character de- 10 scribed, a plate having openings through which players of two opposing teams may be displayed in order in their respective in and out field positions, means beneath said 15 openings to display the players of the opposing teams as required, an endless apron containing various plays which arise during the progress of a game, rollers around which 20 said apron travels, and means coacting with one of said rollers to determine when the apron has moved a predetermined distance.

7. In an apparatus of the character de- 25 scribed, a plate having openings through which players of two opposing teams may be displayed in order in their respective in and out field positions, means beneath said 30 openings to display the players of the opposing teams as required, an apron containing columns of plays which arise during the 35 progress of a game, and means whereby cer- tain columns may be chosen for the display of proper plays as they arise during the 40 progress of a game.

8. In an apparatus of the character de- 45 scribed, a member having openings therein through which different plays may be disclosed, movable means beneath said openings bearing the names of said plays, and means 50 operably connected to said member to normally close said openings, during the operation of said movable means.

9. In an apparatus of the character de- 55 scribed, a member having openings through 40 which players of two opposing teams may be displayed in order in their respective in and out field positions, an annulus having representations of said players spaced thereon in such manner that one operation 45 of said annulus discloses players of one team and another operation of said annulus discloses players of the other team at said openings, and movable means surrounded by said annulus and containing representations of 50 base runners of the opposing teams to be displayed at base openings in the first-mentioned member.

10. In an apparatus of the character de- 55 scribed, a member having openings through 50 which players of two opposing teams may be displayed in order in their respective in and

out field positions, an annulus having representations of said players spaced thereon in such manner that one operation of said annulus discloses players of one team and another operation of said annulus discloses 60 players of the other team at said openings, and independent movable members surrounded by said annulus and containing representations of base runners and pitchers of the opposing teams to be displayed at base openings and a pitcher's opening, respectively, in the first-mentioned member.

11. In an apparatus of the character de- 70 scribed, a member having openings through which players of two opposing teams may be displayed in order in their respective in and out field positions, an annulus having representations of said players spaced thereon in such manner that one operation of said 75 annulus discloses players of one team and another operation of said annulus discloses players of the other team at said openings, independent notary members surrounded by said annulus and containing representations 80 of base runners and pitchers of the opposing teams to be displayed at base openings and a pitcher's opening, respectively, in the first-mentioned member, and means for 85 actuating said rotary members.

12. In an apparatus of the character de- 90 scribed, a member having openings through which players of two opposing teams may be displayed in order in their respective in and out field positions, and an annulus having an inwardly extending tongue and representations of players spaced thereon and on said tongue in such manner that one operation 95 of said annulus discloses certain players of both teams at said openings and another operation discloses certain other players of both teams at said openings.

13. In an apparatus of the character de- 100 scribed, a member having openings therein through which different plays may be disclosed, movable means beneath said openings bearing the names of said plays, means to close said openings during the operation of said movable means, and means to indicate when the plays successively register 105 with the openings.

In testimony whereof I affix my signature, in the presence of two witnesses.
